CLAIM

Applicant claims the ornamental design for display rack, as shown and described.

DESCRIPTION

FIG. 1 is a perspective view of an embodiment of a display rack, with transparent front access panels, visible internal trays, an opaque right side, and a transparent top. The left side is open.

FIG. 2 is a front view of the display rack shown in FIG. 1. FIG. 3 is a top view of the display rack shown in FIGS. 1 and 2.

FIG. 4 is a right side view of the display rack shown in FIGS. 1-3.

FIG. 5 is a left side perspective view of the display rack shown in FIGS. 1-4.

FIG. 6 is a front view of a transparent front panel assembly for a display rack, used in the embodiment shown in FIG. 2. FIG. 7 is a perspective view of another embodiment of a display rack, with transparent front access panels, an opaque right side, and a transparent top. The left side is open, similar to FIG. 1, but with smaller openings than are shown in FIG. 1. Top and side views are generally as shown in FIGS. 3-5 and therefore not shown;

FIG. 8 is a front view of the display rack shown in FIG. 7; FIG. 9 is a front view of another embodiment of a display rack, with transparent front access panels and visible internal trays; and,

FIG. 10 is a perspective view of the display rack shown in FIG. 9, showing an opaque right side and a transparent top. The left side is open. Top and side views are generally as shown in FIGS. 3-5 and therefore not shown.

The broken line(s) shown in the drawings are for illustrative purposes only and form no part of the claimed design. The stippling and shading lines shown in the drawing(s) represent the three-dimensional contour of the design, and are not intended to indicate surface decoration. Throughout the drawings, various views may not be provided, as the components in these views are unornamented or the ornamentation in these views is simply unclaimed.
